UNITED STATES PATENT OFFICE.

ADOLF BOGE, OF SOLINGEN, GERMANY.

LATCH LOCK.

Application filed September 12, 1924, Serial No. 737,285, and in Germany September 12, 1923.

The invention relates to a latch lock provided with a latch capable of being secured or fastened in its locked or unlocked position, which lock may be opened on the one hand by means of a cylinder lock and on the other hand by means of a turnable handle or pressure member. In known locks of this kind the securing or fastening of the latch has been possible only from one side of the door (the inside) and has been effected by a separate knob arranged close to the pressure member.

In connection with locks of this kind it has already been proposed to secure the latch by means of a transverse bolt. In that case there were provided two separate transverse bolts for securing the latch from the outside and from the inside of the door, of which bolts one could be shifted by means of an arm of the boss coupled to the cylinder-lock while, for adjusting the other bolt, there was provided on the inside of the door a separate handle independent of the handle for retracting the latch. Moreover the securing of the latch effected from the inside of the door, could be released from without, while on the other hand the securing effected from the outside could be released only from the outside, but not from the inside. This was attained by the two transverse bolts being coupled together in such manner that the bolt adjustable by the cylinder-lock drove with it in its movement in the direction of latch-retraction the other transverse bolt, while on the other hand in its movement in the direction of latch-release said bolt moved independently of the transverse bolt adjustable by the cylinder lock.

According to the present invention, this proposed lock is very considerably simplified in construction and operation in that, for securing the latch from the outside and inside of the door, only a single transverse bolt is provided, which can be operated both by the arm of the boss coupled to the outside cylinder-lock and by the arm of the inside handle-boss or cylinder lock. In this case of course provision must be made by suitable co-ordination of the two boss-arms and the abutment on the transverse bolt-coating with them that the arm of one boss does not prevent movement of the bolt by the arm of the other boss. The arrangement may be such that the latch secured by means of the inside handle may be released by means of the outside cylinder-lock and vice

versa. The lock moreover may, as is known per se, be so arranged that the latch secured by means of the outside cylinder lock cannot be retracted by means of the inside handle, as will be necessary in many cases to prevent burglars from opening the door from the inside after they have broken open the window possibly fitted to the door. To this end in the new lock the plate-like abutment or stop on the transverse bolt for retracting the latter need merely be provided with a slot into which the arm of the inside handle-boss enters and is consequently rendered inoperative when the bolt is moved by the other boss in the securing position.

One embodiment of the invention is illustrated by way of example in the accompanying drawings wherein,

Figs. 1 to 3 are views of the new lock with cover removed in three different positions,

Fig. 4 is an interior view of the lock cover with a boss journaled therein, the latch and transverse bolt being shown in dotted lines,

Fig. 5 is a horizontal section and

Fig. 6 a vertical section of the lock and door, and

Fig. 7 is a plan view of the transverse bolt.

The embodiment shown is a case lock wherein the latch can be secured from both sides, but the fastening of the latch by means of the cylinder lock cannot be released again by the pressure member. *a* indicates the lock casing which is integral with the bottom *b* and is secured to the inside of the door by means of the lock cover *c* in the usual manner. The main or latch bolt *f* is guided at its head *f*¹ in the flanged portion of the lock, while its stem or body is guided, by means of a rod *g* secured thereon, in an eye provided on the lock-bottom. This rod is provided with a helical spring *h* which tends to press the latch bolt into its closing position. Journaled in the lock-bottom *b* is a boss *k* provided with a rollback arm *k*¹ and rigidly coupled with a turnable handle or pressure member *i* arranged on the outside of the lock-bottom. Journaled in the lock-cover *c* is a second boss *m* which is coaxial with the first and is provided with a rollback arm *m*¹. This boss is coupled in known manner by means of a flat coupling pin *n*¹ with the rotary cylinder of a cylinder lock *n* mounted

in a hole in the door *d* and accessible from outside. The two bosses *k*, *m*, by co-operating with ledges *f*² extending from the two sides of the latch-stem serve in known manner to retract the latch *f* into the lock casing.

According to the invention, in order to secure the latch *f*, there is provided on the lock-bottom a bolt or slide *o* which is guided to move transversely with respect to the latch-stem and which carries a fastening pin *q* engaging in a slot *p* in the latch-stem. The slot in the latch-stem is provided at its lower edge with two seatings or recesses *r*¹, *r*² into which the pin *q* enters when the bolt *o* is in its lower end position in order to secure the latch in its closing position also, if desired, in its retracted position. The pin *q* at the same time constitutes a stop for the arms on the two bosses *k*, *m*, which can so coat with the pin that when the one or the other boss is turned in a direction opposite to that of the opening movement the transverse bolt *o* is shifted by the pressure of the arm on the boss into its lower end position. A second stop for the arms of the bosses is formed by a plate *s* provided at the upper end of the bolt *o* and arranged at right angles to the plane of the bolt, with which plate the said arms coat in the lower end position of the bolt *o* in order to bring the latter back again into its upper end position by turning the boss in the direction of the opening movement. The bolt is retained in its end positions by means of a spring-influenced snap-in bolt *t* which is guided in a transverse hole in the lock-bottom *b* and engages in seatings in the bolt.

The arm of the boss *m* coupled with the cylinder lock *n* takes up the slanting position shown in Fig. 4 when the rotary cylinder is in its locking position, in which slanting position this arm is situated between the two stops *q*, *s*. Moreover, the arm *m*¹ is of such a length that it will not prevent depression of the transverse bolt by the other boss *k*, it being possible, however, to raise the bolt again not only by means of the latter boss but also by means of the boss *m* coupled with the cylinder lock. The arm *k*¹ of the boss coupled with the handle *i* is longer than the arm *m*¹ and in the normal position of the latter takes up the approximately vertical position shown in Fig. 1 in which its curved rear portion lies close above the lower stop *q*, whereas its free end is about on a level with the upper stop *s*. In order that this arm shall not prevent the bolt *o* from being depressed by the boss *m*, this arm being simultaneously somewhat turned in the direction of its opening movement. In this way the result is at the same time obtained that, when the latch *f*

is fastened by the cylinder lock *n*, the boss *k* coupled with the handle *i* is put out of action, so that the transverse bolt cannot then be again raised by the boss *k*. In order to retain the boss *k* and handle *i* in their normal positions a flat spring *v* which is substantially V-shaped is provided, a limb of which presses on a lateral flat on the boss.

The mode of operation of the new lock is set forth in sequence as follows:

The latch *f* can be moved from the closing position shown in Fig. 1 into the opening position shown in Fig. 2 by the cylinder lock *n* or the pressure member *i*, as desired. For this purpose it is necessary only to turn either the rotary cylinder of the cylinder lock *n* or the pressure member *i* in the direction of the opening movement (arrow *x* in Fig. 2 or arrow *y* in Fig. 4). In order to secure the latch *f* which has been shot forward, the handle *i* is turned against the direction of movement for opening, that is, against the direction of the arrow *x*. The transverse bolt *o* is thus moved downwards by the pressure of the arm *k*¹ on the pin *q*, so that the pin *q* engages in the gap *r*¹ in the latch-stem. To release the fastening again, the handle *i* need only be turned in the direction of the opening movement, whereby the arm *k*¹ of the boss *k* in coating with the stop plate *s* shifts the transverse bolt again into its upper end position. Instead of the latch fastening being released by the pressure member *i* it may be released by the cylinder lock *n*, the rotary cylinder of the latter being likewise turned in the direction of the opening movement, the arm *m*¹ of the boss *m* shifting the transverse bolt *o* upwards. In a similar manner to that just described the latch which has been pressed back by hand when the door is open may be fastened in its opening position when the door is not to be retained for the time being. In this case the blocking pin *q* coacts with the gap *r*².

The securing of the latch in its closing position by means of the cylinder lock *n* is effected by the rotary cylinder of the latter being likewise turned against the direction of the opening movement, that is, against that of the arrow *y*, the arm *m*¹ of the boss *m* shifting the transverse bolt *o* into its lower end position. When the lock cylinder is turned in the direction of the opening movement (of arrow *y*) the bolt is again moved upwards and the latch is no longer secured. Should the latch have been secured by means of the cylinder lock it cannot, however, be released by the pressure member *i*. For when the transverse bolt *o* is depressed by the cylinder lock, the boss *k* coupled with the pressure member *i* is put out of action in that its arm *k*¹ enters the slot *u* in the stop plate *s* (cf. the position shown in dotted lines in Fig. 3). The boss can then indeed

be turned in the direction of the opening movement, but it neither influences the transverse bolt nor can it retract the fastened latch.

5 Claims:

1. In a lock, an automatically projectible latch bolt, a second bolt movable transversely of said latch bolt for locking the latter in projected position, and a pair of independently operable bolt controlling members, each operable to effect the projection of the second bolt and the retraction of both bolts.

2. In a lock, a cylinder lock unit, a handle unit, said units being coaxially arranged and each of said units having a rollback, an automatically projectible main bolt, and a second bolt movable transversely of said main bolt for locking said main bolt in projected position, said main bolt being retractable by the rollback of either unit and said second bolt being both projectible and retractable by the rollback of either unit.

3. In a lock, a latch bolt, a second bolt for locking the latch bolt in projected position, and a pair of bolt controlling members each normally independently operable to effect the projection and retraction of both bolts, one of said members being operative in its bolt projecting motion to render the other member ineffective for bolt releasing actions while the said second bolt remains projected and under the control of the first-named member.

4. In a lock, a latch bolt, a second bolt movable transversely of the latch bolt into and out of engagement therewith, and a bolt actuating element movable in reverse directions for bolt projecting and releasing actions, said member having an arm operative on its bolt projecting motion to engage and project said second bolt, and operative on its bolt releasing motion to engage and retract said second bolt and then engage and retract the latch bolt.

45 5. In a lock, a latch bolt having a locking recess, a second bolt movable transversely of the latch bolt, said second bolt having a pair of spaced projections, one of said projections being adapted for locking engagement with said recess, and a bolt actuating member movable in reverse directions for simultaneous bolt projecting and retracting actions, said member having an arm movable between said spaced projections on the second bolt, said arm being operative on the bolt projecting motion to engage one of said contacts and shift the same into engagement with the recess in the latch bolt and operative on the bolt releasing motion to engage the other contact of said second bolt to move the first-named contact out of said recess.

6. In a lock, a latch bolt, a second bolt movable transversely of the latch bolt for engagement therewith and disengagement

therefrom, and a pair of bolt actuating devices each normally independently operative for projecting and retracting the bolts, each of said devices having an arm and said second bolt being provided with a pair of contacts between which said arm is disposed, said arm being movable into engagement with said contacts on reverse movements of the actuating device for shifting said second bolt into and out of locking position.

7. In a lock, a latch bolt, a second bolt movable transversely of the latch bolt and having a pair of spaced projections, one of said projections being movable into and out of locking engagement with the latch bolt, and a pair of bolt actuating devices, each normally operative independently of the other for bolt projecting and retracting actions, each bolt actuating device having an arm movable between the contacts of said second bolt for respectively projecting and retracting the same, the other of said projections and the arms of the actuating devices being so relatively constructed as to render one of said bolt actuating devices ineffective for bolt releasing actions upon the projection of the bolts by the other bolt actuating device and while said bolts are under the control of the latter.

8. In a lock, a latch bolt having a locking recess, a second bolt movable transversely of the latch bolt and having a locking pin movable into and out of engagement with said recess in the latch bolt, a projection on said second bolt spaced from said locking pin and provided with a slot and a pair of contact surfaces, and a pair of rotary bolt actuating members each normally operable independently of the other for bolt projecting and retracting actions, each actuating device being provided with a curved arm for coaction with said locking pin and projection to project and retract said second bolt, the arm of one actuating device being shorter than the other, the short arm of one actuating device being engageable with one contact surface of the projection for retracting said second bolt, and the long arm of the other actuating device being engageable with the other contact surface of said projection for retracting said second bolt, said long arm being movable into the slot of said projection and to a position inoperative for retracting said second bolt following a bolt projecting action by the actuating device having the shorter arm and prior to the retraction of the bolts by the latter-named actuating device.

9. In a lock, a latch bolt, a second bolt movable transversely of the latch bolt for locking the same in projected position and releasing it for retraction, and inside and outside actuating devices, each operative independently in one direction of movement

to successively project the latch bolt and second bolt and in a reverse direction to retract said bolts in inverse order.

10. A lock comprising a casing, a latch bolt slideable therein, spaced interconnected notches formed in said bolt, a second bolt movable transversely of said latch bolt, a pin carried by said second bolt adapted to seat in said notches, and spaced pivoted arms 5 cooperating with said pin for shifting said second bolt to hold said latch bolt in latched or unlatched position.

11. A lock comprising a casing, a latch bolt slideable therein, spaced interconnected notches formed in said bolt, a second bolt 15 movable transversely of said latch bolt, a pin carried by said second bolt adapted to seat in said notches, resilient means for holding said second bolt in its extreme positions, and spaced pivoted arms 20 cooperating with said pin for shifting said second bolt to hold said latch bolt in latched or unlatched position.

12. A lock comprising a casing, a latch bolt slideable therein, spaced interconnected 25

notches formed in said bolt, a second bolt movable transversely of said latch bolt, a pin carried by said second bolt adapted to alternately seat in said notches, resilient means for holding said second bolt in its 30 extreme positions, and spaced individually operable pivoted arms for shifting said latch bolt and cooperating with said pin for shifting said second bolt to hold said latch bolt in latched or unlatched position. 35

13. In a lock, a cylinder lock unit, a handle unit, said units being coaxially arranged and each of said units having a rollback, a spring-projected main bolt directly engageable and retractable by the rollback of either 40 unit, and a second bolt movable transversely of said main bolt for locking said main bolt in projected position, said second bolt being directly engageable and projectible and retractable by the rollbacks of both the cylinder and the said handle units. 45

In testimony whereof I affix my signature.

ADOLF BOGE.
